SURFACE GENERATOR FOR GLASS

Warren E. Ashenfelder, Gardena, Robert P. Johnson, Pasadena, and Nathan T. Wilcox, Arcadia, Calif., assignors to Northrop Aircraft, Inc., Hawthorne, Calif., a corporation of California

Application August 26, 1955, Serial No. 37,670

Term of patent 14 years

(Cl. D37—1)

Figure 1 is a view in perspective of the surface generator for glass, showing our new design thereof, the opposite side being identical to that shown; and

Figure 2 is a rear view thereof on reduced scale of the surface generator for glass shown in Figure 1.

We claim:

The ornamental design for a surface generator for glass, substantially as shown and described.
